UNITED STATES PATENT OFFICE.

ELMER P. GUMMO, OF MONUMENT, PENNSYLVANIA.

WRENCH.

1,074,547.

Specification of Letters Patent. Patented Sept. 30, 1913.

Application filed January 23, 1913. Serial No. 743,860.

To all whom it may concern:

Be it known that I, ELMER P. GUMMO, a citizen of the United States, residing at Monument, in the county of Center and 5 State of Pennsylvania, have invented new and useful Improvements in Wrenches, of which the following is a specification.

My invention relates to a new and useful improvement in double acting mechanism 10 for wrenches and like tools, and has for its object to so construct such a device that the jaws of a wrench may be quickly adjusted to the nut or other object to be acted on and thereafter, a powerful grip taken upon 15 said work, which grip may be relieved by a reverse manipulation of the device which will greatly facilitate the operation of the wrench, saving time and labor.

With these ends in view, this invention 20 consists in the details of construction and combination of elements hereinafter set forth and then specifically designated by the claims.

In order that those skilled in the art to 25 which this invention appertains may understand how to make and use the same, I will describe its construction in detail, referring by numeral to the accompanying drawing forming a part of this specification, in which—

Figure 1, is a central section of a wrench made in accordance with my improvement, the movable jaw and shank thereof being left in elevation. Fig. 2, is an enlarged 35 section of the handle, showing the operating mechanism therein in elevation. Fig. 3, is an end view of the stationary jaw showing the shank thereof in end elevation. Fig. 4, is a face view of the clutch, and Fig. 5, is 40 an end view of the threaded sleeve showing the teeth for engagement with the clutch. Fig. 6 is a face view of the washer.

In carrying out my invention as here embodied, 1 represents the stationary jaw of a 45 monkey wrench, and 2 the movable jaw thereof. This stationary jaw has projecting therefrom, a shank 3, which gradually tapers toward its outer end, the sides thereof being flattened as clearly shown in Fig. 50 3, for the purpose to be hereinafter explained.

The movable jaw 2, has formed therewith a hollow shank 4, the opening through this shank being of a shape to fit upon the shank 3, and slide thereon, but hold it 55 against rotation.

The shank 3, is reduced in diameter as shown at 5, to produce a shoulder 6, and against this shoulder is placed a washer 7, against which bears one end of the coiled spring 8, the other end bearing against the clutch 9 which is slidably mounted upon the reduced section 5 of the shank 3, and as the sides of this reduced section 5 are flat and the opening 10 in the clutch 9 corresponds to the cross section of this reduced portion, said clutch will be prevented from turning thereon. The outer end of the shank 3, is further reduced to form a spindle 27 which is round in cross section, and provided with a thread 29 on which is run the nut 12, and on this spindle is journaled the sleeve 11, held in place by said nut. The extreme end of the shank is further reduced in size and provided with a thread 30 of different pitch 60 from the thread 29 and on this is run the jam nut 12a. The outer end of the sleeve 11, is reduced in diameter as shown at 13 forming a flange 14 and around this reduced portion is placed a washer 15 and between this washer and the flange 14, is placed a spring 16. The flange 14 and spring 16 are surrounded by the ring 17, the purpose of said ring being to actuate the clutch 9 as hereinafter explained. The 65 outer end of the sleeve 11 has the teeth 18 formed thereon for engagement with the teeth 19 of the clutch when the latter is forced into engagement with said sleeve by the spring 8.

The shank 4 of the movable jaw 2, is threaded as indicated at 20 and these threads engage the internal threads of the section 21 of the handle, the section 22 of said handle being secured as by threads 95 23 and the section 21 serves as a hand-hold or grip for operating the wrench. The section 22 has internal threads 24 formed in a portion thereof and these threads engage with the external screw 100 threads 25 formed on the sleeve 11 and it is to be noted that these threads 25 are of less pitch than the threads 20 formed on the shank 4, the object of which will be presently explained.

26 is a cap threaded or otherwise secured upon the end of the section 22 for inclosing the nuts 12.

From the foregoing description, the operation of my device will be as follows:— 110 Assuming that the threads 20 have a pitch of $5/64$ of an inch and the threads 25 a

pitch of 4/64 the revolving of the handle in the proper direction will cause the movable jaw 2 to be drawn away from the stationary jaw 1, first at a rate equal to the difference 5 between the threads 20 and the threads 25 which in the case here stated, will be 1/64 of an inch for each revolution of the handle, from the fact that the sleeve 11 on which the threads 25 are formed, is held against rotation upon the spindle 27 by the clutch 9 being in engagement with the teeth of said spindle as before stated. This will continue until the shoulder 28 formed on the inside of the section 22 of the handle comes 10 in contact with the washer 15 and through said washer forces the ring 17 forward to a sufficient distance to disengage the clutch against the action of the spring 8 from the teeth 18 on the end of the sleeve after which 15 the sleeve will revolve with the handle, cutting out the action of the threads 25 and causing the jaw 2 to move 5/64 of an inch for each turn of said handle. This will give a rapid opening of the jaws as will be 20 readily understood. When the jaws are to be applied to a nut or other object the handle is turned in the opposite direction from that just described and as the clutch is still disengaged from the sleeve, the jaw 2 will 25 be moved rapidly toward the nut until a certain amount of grip is taken upon said nut which will create a friction by thrust between the outer end of the sleeve and the inner nut 12, and when this friction becomes 30 sufficient to stop the rotation of the sleeve 11, the threads 25 will again come into action and as the handle travels longitudinally on this sleeve, the washer 15 will be permitted to be forced backward by the spring 16, 35 thus allowing the spring 8 to again force the clutch into engagement with the teeth 18 on the end of the sleeve thereby locking said sleeve positively against rotation and the continued revolving of the handle in the 40 same direction will cause the jaw 2 to move at a reduced rate represented by the difference between the pitch of the threads 20 and the threads 25, namely 1/64 of an inch for each turn of the handle and as is well 45 understood, this reduced rate of movement for each turn of the handle increases the power applied to the jaws. This arrangement provides for quick action in adjusting the jaws of the wrench to the work, but when 50 said jaws have taken hold of the work, it provides for a powerful grip and thus saves time and labor. It will be understood that my improvement may be applied to various other tools in which it is desirable to have, 55 first a quick action which may afterward be converted into a powerful grip as for instance lathe and drill chucks.

Where it is found desirable, the outer end of the sleeve or the surface which comes in 60 contact with the inner nut 12 may be cor-

rugated or roughened and the inner surface of said nut correspondingly corrugated or roughened to increase the friction caused by the thrust for temporarily arresting the rotation of the sleeve 11 until the clutch is 70 brought into action or a leather or other compressible washer may be interposed between these to serve for a like purpose.

Of course I do not wish to be limited to the exact details of construction as here 75 shown as these may be varied within the limits of the appended claims without departing from the spirit of my invention.

Having thus fully described my invention, what I claim as new and useful is,— 80

1. In a tool, the combination of a shank, a hollow shank fitted to slide on the first named shank, a sleeve journaled on the first named shank, screw threads formed on the hollow shank and on the sleeve the 85 two sets of threads being of different pitch, a handle member having two sets of threads, one set engaging the threads on the hollow shank, the other set engaging the threads on the sleeve and means for automatically 90 causing the sleeve to revolve with the handle member or remain stationary relative to the rotation of said handle member for changing the rate of travel of the hollow shank.

2. In a tool, the combination of a stationary shank, a sleeve journaled thereon, a hollow shank fitted to slide on the stationary shank, screw threads formed on the hollow shank and on the sleeve, the two sets of threads being of different pitch, a handle 100 member having two sets of internal threads, one set engaging the threads on the hollow shank, the other set engaging the threads on the sleeve, a spring actuated clutch held against rotation on the stationary shank and 105 means for automatically locking said clutch into engagement with the sleeve and unlocking said clutch from said sleeve.

3. In a tool, the combination of a stationary shank carrying a jaw, a movable shank 110 fitted to slide upon the stationary shank and also carrying a jaw, a sleeve journaled on the stationary shank, screw threads formed on the movable shank and on the sleeve, the two sets of threads being of different pitch a handle member having two sets of internal threads, one set engaging the threads on the movable shank, the other set engaging the threads on the sleeve, means dependent upon the thrust caused by the 115 closing of the jaws upon an object for automatically holding the sleeve against rotation, a clutch adapted to positively lock said sleeve against rotation and means for automatically locking and unlocking said clutch. 120

4. In a wrench, a stationary shank, a jaw carried thereby, a movable shank, a jaw carried thereby, threads of relatively steep pitch formed upon the movable shank, a sleeve journaled on the end of the stationary 130

shank, screw threads formed on the sleeve of less pitch than the threads on the shank, a hollow handle having one set of internal screw threads for engagement with the 5 screw threads on the movable shank, and another set of screw threads for engagement with the screw threads on the sleeve, a nut threaded upon the stationary shank for holding the sleeve in position and exerting 10 a certain amount of friction thereon by the end thrust between the shanks, a spring actuated clutch mounted on the stationary shank, and held against rotation thereon, teeth formed upon the clutch, corresponding 15 teeth formed upon the adjacent end of the

sleeve and means for automatically putting the clutch into and out of engagement with the teeth on the sleeve, whereby the screw threads on the sleeve will be brought into or put out of action to cause the movable jaw 20 to move at different rates of travel by the rotation of the handle as specified.

In testimony whereof, I have hereunto affixed by signature in the presence of two subscribing witnesses.

ELMER P. GUMMO.
